UNITED STATES PATENT OFFICE.

AUSTINE S. McDERMOTT, OF MELLERAY, IOWA.

PROP.

SPECIFICATION forming part of Letters Patent No. 240,437, dated April 19, 1881.

Application filed September 20, 1880. (No model.)

To all whom it may concern:

Be it known that I, AUSTINE S. McDERMOTT, of Melleray, in the county of Dubuque and State of Iowa, have invented a new and useful Improvement in Props; and I do hereby declare that the following is a full and exact description of the same, reference being had to the accompanying drawings, and to the letters of reference marked thereon.

10 In the use of thrashing-machines, hullers, and other portable machinery used in agriculture it is found when the machine is at work that the motion produces a lateral movement of the entire machine, extremely inconvenient in practice, and also a considerable vibration and shaking of the outer casing, which is very injurious, rendering the wear and tear of the wooden frame-work much greater than it would be were the structure motionless, and tending 20 to cause the falling to pieces of the machine. The ordinary custom in this case is to prop up each side of the machine with any straight pole or piece of wood which may be at hand; but the inconvenience of this plan is obvious. 25 A straight prop is extremely difficult of adjustment, and requires to be arranged differently for different places where the machine may be set up, or for different machines, and, besides, is almost certain to work loose in a 30 short time, rendering necessary a complete stoppage of the work and an entire readjustment of the apparatus. It will thus be seen that some arrangement is necessary whereby a prop may be obtained which is always at hand, is perfectly easy of adjustment, may be used at any angle or elevation or with a machine of any size, and has no tendency to work loose and fall from its position.

Such an apparatus I propose to furnish in 40 my invention, which consists in a prop or brace made in two pieces, pivoted together in such a manner that the whole may be lengthened or shortened, or placed at any desired angle, as hereinafter more fully described.

45 In the accompanying drawings, Figure 1 shows my brace or prop with the two parts broken apart or placed at an angle with each other. Fig. 2 shows the prop with its parts in a straight line and clasped together as in use, and Fig. 3 a perspective view of the clasp.

The prop is formed in two parts, A B, loosely

jointed at F by a bolt, on which they turn, as on a pivot. The lower piece, A, is formed into a point, C, at its lower end, that it may be more readily thrust into the ground. It also 55 contains a number of bolt-holes, a a a, &c., of a proper size to contain the bolt F, for the purpose of lengthening or shortening the brace, thus adapting it to be used in any elevation or with a machine of any size. The upper piece, 60 B, contains the bolt F, joining the two parts, and has fastened to it a clasp, D, into which the piece A fits when the parts are folded together, preventing the parts from moving past each other. Also fastened by a pivot to the 65 part B is the button E, which, when the parts are together, is turned so as to secure them in a straight position, as in Fig. 2.

It will be seen that the clasp D prevents the brace from breaking in one direction, and the 70 button E from breaking in the other. It will also be seen that this clasp is constructed so as to form what may be termed an "open clasp." The object of this construction, when the clasp is arranged upon the part B, as heretofore described, is to allow a free pivotal movement of said part B, in conjunction with the part A and the bolt F, connecting said parts.

The lower end of B is formed into a handle 80 for convenience of manipulation, while the upper end is shaped so as to bear against a cleat nailed to the side of the structure to be stayed.

The manner of operating this device is as follows: The button E being turned back and 85 the brace unlocked, the point C is driven into the ground. Then, by means of the handle, the brace is broken apart and upward. The upper end of B is placed under the cleat, nailed for that purpose to the side of the machine, and the handle again pressed downward 90 until the part A enters the clasp D and the brace becomes straight, when the button E is turned, thus locking the brace. It is thus firmly maintained in a straight position.

To adapt the device for use with a machine of a different size the bolt F is withdrawn and thrust into a higher or a lower hole, as the case may be.

In practice it is of course necessary to use 100 two braces, one on each side of the machine.

It will thus be seen that I have invented a

brace or prop simple of construction, easy of adjustment, and which will always maintain itself in any required position, thus supplying a long-felt want.

5 What I claim as my invention is—

A brace for supporting thrashing-machines consisting of the part A, containing the bolt-holes *a a*, and the part B, carrying the open clasp D, button E, and bolt F, the two parts

being adjustably pivoted together and the whole arranged to be operated substantially as described, and for the purpose set forth.

This specification signed and witnessed this 3d day of September, 1880.

AUSTINE SYLVESTER McDERMOTT.
